CLAIM

The ornamental design for a greeting card with enclosure, as shown and described.

DESCRIPTION

FIG. 1 is a top, front, right side perspective view of a first embodiment of a greeting card with enclosure showing the new design;

FIG. 2 is a front elevation view thereof;

FIG. 3 is a left side elevation view thereof;

FIG. 4 is a right side elevation view thereof;

FIG. 5 is a top plan view thereof;

FIG. 6 is bottom plan view thereof;

FIG. 7 is a top, front, right side perspective view of a second embodiment of the greeting card with enclosure;

FIG. 8 is a top, front, right side perspective view of a third embodiment of the greeting card with enclosure; and,

FIG. 9 is a top, front, right side perspective view of a fourth embodiment of the greeting card with enclosure.

The broken lines in the drawings are included to show environmental structure and portions of the article that form no part of the claimed design.
